COMBINATION ELECTRIC AND ELECTRONIC OVENS
Louis H. Fitzmayer, Louisville, Ky., assignor to General Electric Company, a corporation of New York
Filed Sept. 1, 1961, Ser. No. 135,582
22 Claims. (Cl. 219—10.55)

The present invention relates to electronic ovens and specifically to combined electric and electronic ovens, and more particularly to ultra-high frequency electromagnetic wave energy transmission and cooking platform constructions for such ovens.

It is a general object of the invention to provide in an electronic oven an improved transmission line of the type including a tubular outer conductor and an enclosed inner conductor for transmitting ultra-high frequency electromagnetic wave energy from a generator to the cooking cavity in the interior of the oven.

Another object of the invention is to provide in an electronic oven an improved transmission line of the type set forth including alternating sections, wherein the first and other odd numbered transmission line sections are of the type including a tubular outer conductor having a substantially circular cross section and an enclosed inner conductor having a substantially circular cross section, and wherein the second and subsequent even numbered transmission line sections are of the type including a tubular outer conductor having a substantially rectangular cross section and an enclosed inner conductor having a substantially rectangular cross section.

In connection with the foregoing object, it is another object of the invention to provide in an electronic oven an improved transmission line which is more easily and economically constructed, maintained and repaired, particularly when the transmission line includes a plurality of bends including right angle bends.

Yet another object of the invention is to provide in an upstanding electronic oven of the type having an upper box-like metal liner including a top wall and defining a cooking cavity and a lower apparatus compartment containing a generator of ultra-high frequency electromagnetic wave energy, an improved distribution box mounted on the top wall which better distributes within the cooking cavity the electromagnetic wave energy transmitted thereto from the generator.

In connection with the foregoing object, it is another object of the invention to provide a combined electric and electronic oven having an improved arrangement of a distribution box mounted on the upper surface of the top wall thereof and cooperating with electric heating units of the resistance conductor type mounted on the lower surface of the top wall so as to achieve better electric and electronic cooking without interference one with the other.

A further object of the invention is to provide an improved electronic oven including a cooking cavity having a top wall supporting a distribution box thereon and a generator disposed beneath the cooking cavity with a transmission line including angularly disposed sections extending upwardly from the generator and substantially horizontally rearwardly and upwardly along the back of the cooking cavity and substantially horizontally across the top of the cooking cavity to the distribution box, there being substantially right angle connections between the transmission line sections extending substantially horizontally and the transmission line sections extending upwardly.

Further features of the invention pertain to the particular arrangement of the parts and elements of the electronic oven, whereby the above-outlined and additional operating features thereof are attained.

2

The invention both as to its organization and method of operation, together with further objects and advantages thereof, will best be understood by reference to the following specification taken in connection with the accompanying drawings, in which:

FIGURE 1 is a side view with certain parts broken away of a combination electric and electronic oven embodying the present invention;

FIG. 2 is a fragmentary view in vertical section on an enlarged scale showing the interconnection between the magnetron, the lower vertical transmission line section and the lower horizontal transmission line section;

FIG. 3 is a side elevational view on an enlarged scale with certain parts broken away of the lower portion of the upper vertical transmission line section and the connection thereof to the lower horizontal transmission line section;

FIG. 4 is a view in vertical section through the lower horizontal transmission line section along the line 4—4 of FIG. 3;

FIG. 5 is a view in horizontal section through the upper vertical transmission line section along the line 5—5 of FIG. 3;

FIG. 6 is a view in horizontal section along the line 6—6 of FIG. 3;

FIG. 7 is an enlarged fragmentary view in vertical section illustrating the connection between the upper horizontal transmission line section and the distribution box;

FIG. 8 is a view in horizontal section along the line 8—8 of FIG. 7;

FIG. 9 is a side elevational view with certain parts in section illustrating the junction between the upper vertical transmission line section and the upper horizontal transmission line section;

FIG. 10 is a view in vertical section along the line 10—10 of FIG. 9;

FIG. 11 is a fragmentary plan view of the top wall of the cooking cavity as seen in the direction of the arrows along the line 11—11 of FIG. 1;

FIG. 12 is a view in horizontal section, with certain portion broken away, as seen in the direction of the arrows along the line 12—12 of FIG. 1 and illustrating the relationship between the cooking platform and the underlying drip tray;

FIG. 13 is a fragmentary view in horizontal section along the line 13—13 of FIG. 1; and

FIG. 14 is a fragmentary view in perspective illustrating the construction of the cooking platform.

Referring to FIG. 1 of the drawings, the combination electric and electronic oven there illustrated and embodying the features of the present invention is generally designated by the numeral 10 and comprises an oven chamber or cooking cavity 11 defined by electrical conductive walls, and particularly by a box-like metal liner 12 including a top wall 13, a bottom wall 14, a rear wall 15 and two side walls 16, the front opening of the liner 12 being closed by a metallic oven door 17. The door 17 is provided with a hinge 17a and a handle 17b, whereby the door 17 can be moved between an open position and a closed position, suitable interlocking and switching apparatus (not shown) being provided to insure that there is no electromagnetic wave energy present within the cooking cavity 11 when the door 17 is in its open position.

Disposed below the upper cooking cavity 11 is an apparatus compartment 70 within which is disposed a generator in the form of a magnetron 90 which serves as a source of ultra-high frequency electromagnetic wave energy for the cooking cavity 11, the magnetron 90 being of conventional form and having, for example, an operating frequency of 915 megacycles. The electromagnetic

wave energy from the magnetron 90 is transmitted to the cooking cavity 11 via a transmission line of the coaxial conductor type made in accordance with and embodying the principles of the present invention and including four sections 100, 200, 300 and 400 connected in series and communicating with the interior of the cooking cavity 11 through a distribution box 50. More specifically, the magnetron 90 is disposed beneath the cooking cavity 11 and toward the rear thereof and is provided with a lower vertically extending transmission line section 100 of circular configuration connecting at a right angle with a lower horizontal transmission line section 200 of rectangular configuration which extends to a point below and to the rear of the rear wall 15 of the cooking cavity 11. The rear end of the transmission line section 200 is connected at a right angle to the lower end of an upper vertical transmission line section 300 of circular configuration which has the upper end thereof connected at a right angle to the rear end of an upper horizontal and forwardly extending transmission line section 400 of rectangular configuration having the front end thereof connected at a right angle to the distribution box 50. The magnetron 90 is provided with a field coil housing 91 including a central cylindrical member providing a metallic tubular outer conductor 110 that is substantially circular in cross section and has disposed centrally thereof a metallic stud 150 connected to the output terminal of the magnetron 90 and spaced from the conductor 110 by insulators including an insulator 160, the stud 150 being substantially circular in cross section (see FIG. 2 also). The tubular outer conductor 110 and the enclosed inner conductor or stud 150 comprise the first section 100 of the transmission line interconnecting the magnetron 90 and the distribution box 50 mounted on the upper surface of the top wall 13 defining the cooking cavity 11.

In accordance with the present invention, it has been found that substantial and important advantages are obtained if the next or second section 200 of the transmission line connecting at right angles with the first section 100 is a transmission line section of rectangular configuration as illustrated in FIGS. 2 and 4 of the drawings. More specifically, the transmission line section 200 includes a metallic tubular outer conductor 210 that is substantially rectangular in cross section as may be best seen from FIG. 4 of the drawings and includes wider upper and lower side walls 211 and 212 joined by narrower side walls 213 and 214.

A readily separable connection between the transmission line sections 100 and 200 is desirable and to this end there is provided a metallic circular fitting 230 including a cylindrical side wall 231 having a normal external diameter slightly greater than the internal diameter of the tubular conductor 110 and slightly less than the width of the wall 212, and further provided with longitudinal slots 232 thereon so that the fitting 230 can be inserted into the conductor 110 and resiliently held therein. The upper end of the wall 231 has a portion 233 of reduced diameter extending through a circular opening 215 in the lower wall 212 of the outer conductor 210, the outer end of the portion 233 being turned over and crimped down as at 234 firmly to interconnect the fitting 230 and the tubular outer conductor 210.

The end of the conductor 210 adjacent to the fitting 230 is closed by an end cap 220 having a flange 221 adapted to fit within the rectangular conductor 210, the end cap 220 being held in position by means of screws 222. Disposed within the outer conductor 210 and enclosed thereby is a metallic inner conductor 250 which also has a rectangular cross section and is of ribbon-like configuration as can be best seen in FIG. 4 of the drawings, the inner conductor 250 being disposed centrally of the outer conductor 210 and with the flat surfaces thereof substantially parallel to the side walls 211 and 212. The end of the inner conductor 250 adjacent to the magnetron 90 is mounted on the outer conductor 210 by means of a suit-

able insulating block 240 which is held in position by a screw 241 engaging the conductor 210, a screw 242 connecting the adjacent end of the inner conductor 250 with the insulating block 240 and also mounting thereon a resilient metallic connector or bullet 260 which releasably and grippingly engages the stud 150. The resilient circular fitting 230 in combination with the connector 260 provides for ready assembly and connection of the second transmission line section 200 to the first transmission line section 100 during construction and assembly, and further facilitates ready separation thereof during maintenance and repair.

As may be best seen in FIG. 1 of the drawings, the transmission line 200 extends rearwardly from the magnetron 90 and the rear end thereof is closed by a metallic end cap 270 having an annular flange 271 therearound fitting into the interior of the conductor 210 and enclosing the rear end thereof, the end cap 270 being held in position by screws 272 (see FIG. 3 also). The rear end of the conductor 250 terminates a short distance from the end cap 270 and is supported by an insulator block 280 held in position within the outer conductor 210 by means of a screw 281. A threaded metallic stud 282 fixes the adjacent end of the inner conductor 250 on the insulator 280 and further supports a metallic stud 283 thereon which extends through a circular opening 216 provided in the top wall 211 of the outer conductor 210. In order to provide a right angle connection and a readily separable connection 290 between the rear end of the transmission line section 200 and the lower end of the transmission line section 300, a metallic circular fitting 291 is provided having a diameter less than the width of the wall 211 and having a portion 293 of reduced diameter extending through the opening 216 and having the lower end thereof turned over and crimped as at 294 fixedly to mount the fitting 291 upon the upper wall 211 of the outer conductor 210. Disposed about and grippingly engaging the outer surface of the circular fitting 291 is a cylindrical insulating sleeve 295 formed of any suitable insulating material, a preferred material being a synthetic organic plastic resin formed of tetrafluoroethylene polymers sold under the trademark "Teflon," the insulating sleeve 295 extending beyond the upper end of the circular fitting 291 and having an external diameter substantially equal to the external diameter of the tubular outer conductor of the transmission line section 300, as will be explained more fully hereinafter. Surrounding the insulating sleeve 295 is a cylindrical metallic sleeve 296 which closely interfits with the sleeve 295 and extends substantially beyond the upper end thereof and has an internal diameter slightly greater than the external diameter of the tubular outer conductor of the transmission line section 300, the upper end of the sleeve 296 being slotted to provide resilient gripping fingers thereon. Disposed upon the upper end of the stud 283 is an insulating washer 284 which may also be formed of tetrafluoroethylene polymers, and disposed upon the upper surface of the washer 284 is a hollow metallic tube 287 having at the upper end thereof a connecting portion 289 of greater diameter. Disposed within the tube 287 is a metallic probe 285 threaded at the lower end thereof as at 286 and extending through the washer 284 and engaging a complementarily threaded opening in the stud 283. The upper end of the probe 285 has an insulating washer 288 formed, for example, of the tetrafluoroethylene polymers disposed therein and provided with an outwardly extending flange resting upon the shoulder formed at the junction between the tube 287 and the connecting portion 289 at the upper end thereof. A screw 285a extends through the washer 288 and engages the probe 285 to mount the parts in the assembled position illustrated in FIG. 3.

The construction of the transmission line section 300 which extends upwardly from the transmission line section 200 along the rear of the cooking cavity 11 and above the top wall 13 thereof can be best seen from FIGS. 3, 5 and 9 of the drawings. A metallic tubular outer con-

ductor 310 is provided having a cross section that is substantially circular, as can be best seen in FIG. 5, and disposed substantially concentric therewith is an enclosed metallic inner conductor 350 which also has a substantially circular cross section. The lower end of the outer conductor 310 is received within the upper slotted end of the outer metallic sleeve 296 forming a part of the readily separable connection 290 and is in alignment with the circular fitting 291 which is in communication with and attached to the outer conductor 210. Although there is communication between the outer conductors 210 and 310 to facilitate the transmission of electromagnetic wave energy therethrough, there is no D.C. connection therebetween, isolation being provided by the insulating sleeve 295, whereby the relatively high D.C. potentials on the outer conductor 210 are not applied to the outer conductor 310, the outer conductor 310 in fact being grounded as will be explained more fully hereinafter. The lower end of the inner conductor 350 is provided with an enlargement 351 which is provided with slots 352 to facilitate insertion thereof into the connecting portion 289 on the upper end of the inner conductor 287. The parts thus described, including the lower end of the outer conductor 310 cooperating with the outer metallic sleeve 296 and the lower end 351 of the inner conductor 350 cooperating with the connecting portion 289 of conductor 287, provide a readily separable connection which facilitates assembly and disassembly of the transmission line sections 200 and 300 disposed substantially at a right angle with respect to each other.

The upper end of the transmission line section 300 is connected at a right angle to the rear end of the transmission line section 400. Referring to FIGS. 9 and 10 of the drawings, it will be seen that the transmission line section 400 is provided with a metallic tubular outer conductor 410 which has a substantially rectangular cross section and includes wider upper and lower walls 411 and 412 connected along the edges thereof by vertically disposed side walls 413 and 414. Disposed within the outer conductor 410 and enclosed thereby is a metallic inner conductor 450 which also is rectangular in cross section and is disposed substantially centrally of the outer conductor 410 with the broadest surface thereof disposed substantially parallel to the top and bottom walls 411 and 412 of the outer conductor 410. The end of the outer conductor 410 disposed adjacent to the upper end of the transmission line section 300 is closed by an end cap 420 provided with an annular flange which is adapted to fit within the outer conductor 410, the end cap 420 substantially filling and closing the outer conductor 410 and being held in position thereon by a screw 421. The adjacent end of the inner conductor 450 is supported within the outer conductor 410 on an insulating block 440 which is held in position upon the conductor 410 by means of a screw 441, a screw 442 connecting the adjacent end of the inner conductor 450 to the insulator 440 and also mounting thereon a metallic connector 443 which has slots therearound providing spring fingers to grip and engage the upper end of the inner conductor 350 which extends through an opening 415 in the lower wall 412 of the conductor 410. Also mounted within and extending through the opening 415 is a fitting generally designated by the numeral 430 and including a metallic cylindrical wall 431 having a plurality of slots therein forming spring fingers grippingly to engage and to make electrical contact with the adjacent end of the outer conductor 310. Integral with the cylindrical wall 431 is a cylindrical portion 433 of reduced diameter which extends through the opening 415 and is crimped over as at 434 to engage the bottom wall 412 of the conductor 410, thus to mount the fitting 431 within the opening 415 therein.

The other or front end of the transmission line section 400 is connected to the distribution box 50, the outer conductor 410 having an outturned flange 460 extending therearound provided with openings therein to receive

screws 461 therethrough. The adjacent end of the inner conductor 450 is mounted upon the lower wall 412 on an insulating block 470 held in position thereon by a screw 471, a screw 472 extending through the inner conductor 450 and engaging the insulating block 470. The free end of the inner conductor 450 extends beyond the end of the outer conductor 410 and through an opening in the adjacent wall of the distribution box 50 and is provided with a downturned flange 451 connecting with an outwardly extending probe 452 disposed below but parallel to the main body of the inner conductor 450.

Referring particularly to FIGS. 1, 7 and 8 of the drawings, it will be seen that the distribution box 50 is formed of metal and includes a pair of elongated side walls 51 and 52 that are joined at the ends thereof by end walls 54 and at the top by a top wall 53, the top wall 53 and the end walls 54 being mutually perpendicular to each other and to the side walls 51 and 52. Connection is made between the distribution box 50 and the transmission line section 400 through an opening 55 in the side wall 51 substantially midway of the ends thereof, as can be best seen in FIG. 8, and substantially midway vertically thereof, as can be best seen in FIG. 7. The opening 55 has a size and configuration like the interior of the outer conductor 410 and a good electrical and sealing connection is made between the wall 51 and the outer conductor 410 by means of a braided metal gasket 480 disposed about the opening 55 and in contacting relationship with the outer conductor flange 460, the screws 461 passing through the flange 460, the gasket 480 and the wall 51 firmly to join these parts thus providing a grounding connection for the outer conductors 310 and 410 to the distribution box 50.

Extending outwardly from the bottom edge of each of the walls 51, 52 and 54 is a shoulder 57 which is adapted to receive a pane 71 of material which is impervious to oven gases but which is highly transparent to the electromagnetic wave energy, a preferred material of construction being a fused mixture of powdered glass and mica sold under the trademark "Mykroy." The lateral extent of the pane 71 is sufficient completely to cover the lower open side of the distribution box 50 and also to cover a window formed in the top wall 13 of the liner 12 and defined by a depressed portion 18 and more specifically by an upturned flange 19 therearound so as to prevent oven gases from passing from the cooking cavity 11 into the distribution box 50. The depressed portion 18 supports a metal braid gasket 72 which serves to seal the opening on the bottom of the distribution box 50, the parts being held in the assembled position by screws 58 and providing a grounding connection from the distribution box 50 to the liner 12.

The distribution box 50 is disposed substantially centrally of the top wall 13 of the liner 12, i.e., it is disposed substantially midway between the front and rear of the liner 12 with the side walls 51 and 52 disposed substantially parallel to the door 17 when in its closed position and with the end walls 54 disposed substantially equal distances from the adjacent side walls 16 of the oven liner 12. The length of the distribution box 50 is equal electrically to substantially one wave length of the electromagnetic wave energy fed thereto from the magnetron 90. As a result of the construction and positioning of the distribution box 50 upon the top wall 13, the electromagnetic wave energy from the magnetron 90 is advantageously distributed throughout the cooking cavity 11 to obtain the optimum operation thereof.

In order to provide means for tuning the magnetron 90 and the transmission line to the cooking cavity 11 thus to obtain more efficient utilization of the electromagnetic wave energy generated, means is provided for tuning the system, see particularly FIGS. 1, 2 and 8 of the drawings. A metallic tuning rod 75 is provided that is mounted in an opening 56 in the side wall 52 substantially centrally thereof tuning rod 75 and clamped

thereto by means of a lock nut 76, the axis of the tuning rod 75 extending in general alignment with the axis of the body of the inner conductor 450 and over the offset probe 452 thereof. The tuning rod 75 extends beyond the side wall 52 and receives a second adjustment fitting 77, the lock nuts 76 and the adjustment fitting 77 permitting adjustable positioning of the tuning rod 75 with respect to the distribution box 50 and the inner conductor 450, movement of the tuning rod 75 changing the capacity of the offset probe 452 on the inner conductor 450.

As illustrated in the drawings, the appliance 10 is a combination electric and electronic oven and includes a pair of spaced apart electric heating units of the sheathed resistance conductor type mounted on the lower surface of the liner top wall 13 and generally designated by the numeral 20, see FIGS. 1 and 11 of the drawings. The terminal mountings 21 for the heating units 20 are preferably disposed to the left when viewed through the oven door 17 and the heating units 20 are generally rectangular and extend to the right substantially parallel to the oven door 17 and to the longitudinal axis of distribution box 50, one of the heating units 20 being disposed to the front of the distribution box 50, i.e., toward the door 17, and the other heating unit 20 being disposed to the rear of the distribution box 50 so that the heating units 20 do not interfere with the feeding of the electromagnetic wave energy from the distribution box 50 through the pane 71 into the cooking cavity 11.

A lower electric heating unit of the sheathed resistance conductor type is also mounted slightly above the bottom wall 14 of the liner 12 and is generally designated by the numeral 60. The general configuration of the heating unit 60 can be seen in FIG. 13 of the drawings, the terminals 61 for the heating unit 60 extending through the rear wall 15 substantially midway between the side edges thereof and being spaced relatively close together. Heating unit sections 62 extend outwardly from the terminals 61 toward the side edges of the liner 12 and join with side section 63 disposed along the side walls 16 but spaced slightly therefrom, the side sections 63 connecting with a forward U-shaped section 64 interconnecting the side connections 63.

Disposed above the bottom wall 14 of the liner 12 and also above the bottom heating unit 60 is a cooking platform generally designated by the numeral 30 (see FIGS. 1, 12 and 14) and including a central substantially imperforate metallic hub 31 from which extend radially outwardly a plurality of metallic rod-like arms 42 which carry thereon a floor 33 of metallic open-work construction, the outer ends of the arms 32 and the periphery of the floor 33 carrying a circular upstanding metallic rim 34 thereon. Formed integral with the hub 31 and extending downwardly therefrom is an arbor 35 that fits into a bearing 36 mounted on the bottom wall 14 and containing a drive connection 81 for the arbor 35 to a drive unit 80 mounted in the apparatus compartment 70, the drive unit 80 being preferably an electric motor. Food to be cooked is placed upon the cooking platform 30 and the platform 30 is in turn driven by means of the drive unit 80 and the drive connection 81 and the arbor 35 at a rate of 6 revolutions per minute, for example, whereby to pass the food upon the platform 30 through the electromagnetic field within the cooking cavity 11 so that various portions of the food being cooked are subjected to different field intensities, thereby equalizing the cooking thereof.

In order to collect the drippings and juices that are generated and which may fall from the cooking platform 30, a drip tray generally designated by the numeral 40 is provided beneath the cooking platform 30 but above the electric heating unit 60 so as to protect the electric heating unit 60 from the drippings, see FIGS. 1 and 12 of the drawings. The drip tray 40 includes an outer metallic wire frame 41 which extends therearound and which is adapted to hold the main portion of the drip

tray 40 in proper operative position and to mount the drip tray 40 upon the usual embossments 16a provided upon the side walls 16 of the liner 12. The body 42 of the drip tray 40 is formed of metal, is substantially flat and is provided around the outer periphery thereof with an upstanding and outwardly directed rim 43 attached to the frame 41 and provided centrally thereof with an upstanding rim 44 around an opening 45 therein which receives the arbor 35 therethrough. The horizontal extent of the hub 31 is sufficient so that it overlies the opening 45 in the drip tray 40 and directs drippings onto the upstanding rim 44 therearound so as to catch substantially all of the drippings from food on the cooking platform 30 in the drip tray 40.

From FIGS. 1 and 12 of the drawings, it will be seen that the bottom wall 14 of the liner 12 is substantially square and that the axis of the arbor 35 is disposed substantially centrally thereof and centrally with respect to the distribution box 50 on the top wall 13. The diameter of the cooking platform 30 is only slightly less than the length of one side of the bottom wall 14 thereby providing a maximum area of support for food to be cooked. As has been noted above food placed on the cooking platform 30 will be rotated upon operation of the drive motor 80 so as to carry each portion of the food through field positions of varying strengths so as to obtain maximum utilization of the power injected into the cooking cavity 11 and so as more evenly and more thoroughly to cook the food upon the cooking platform 30.

The dimensions of the drip tray 40 are such that it will catch substantially all of the drippings from the cooking platform 30 as has been noted above, the hub 31 shielding the opening 45 from the drip tray 40 to prevent drippings falling upon the bearing 36 and the associated drive mechanism. The cooking platform 30 is readily clean in that the entire platform 30 with the arbor 35 attached can be removed by simply lifting the platform 30 upwardly and withdrawing it from the cooking cavity 11 through the opening provided by the oven door 17. The drip tray 40 is also removable with its associated frame 41 upon removal of the arbor 35 so as to permit ready cleaning thereof.

The drip tray 40 when in position performs the further function of shielding the lower electric heating unit 60 from the electromagnetic wave energy, the drip tray 40 being formed of metal and providing an effective choke for the wave energy throughout substantially the lower portion of the cooking cavity 11, whereby to prevent the formation of parasitic currents in the lower heating unit 60, thereby protecting the heating unit 60 and preventing loss of electromagnetic wave energy therein. However, the side edges of the body 42 of the drip tray 40 are spaced inwardly from the side walls 16 of the liner 12 to accommodate ready circulation of oven air over and into contact with the heating unit 60 disposed below the drip tray 40.

While there has been described what is at present considered to be the preferred embodiment of the invention, it will be understood that various modifications may be made therein and it is intended to cover in the appended claims all such modifications that fall within the true spirit and scope of the invention.

What is claimed is:

1. An electronic oven comprising upstanding structure defining a lower apparatus compartment and an upper box-like metal liner defining an upper cooking cavity, a generator disposed in said apparatus compartment for supplying ultra-high frequency electromagnetic wave energy, and a transmission line of the coaxial conductor type interconnecting said generator and said cooking cavity and including first and second sections disposed at an angle with respect to each other, whereby the electromagnetic wave energy is supplied into said cooking cavity via said transmission line from said generator, said first trans-

mission line section including a first tubular outer conductor having a substantially circular cross section and a first enclosed inner conductor having a substantially circular cross section, said second transmission line section including a second tubular outer conductor having a substantially rectangular cross section and a second enclosed inner conductor having a substantially rectangular cross section, one end of said first outer conductor abutting and joining a side wall of said second outer conductor and surrounding an opening provided therein and the adjacent end of said first inner conductor projecting through said opening and abutting and joining a side wall of said second inner conductor.

2. The electronic oven set forth in claim 1, wherein said second inner conductor is of ribbon-like configuration.

3. The electronic oven set forth in claim 1, wherein said first outer conductor joins said second outer conductor on a side wall thereof of greater width, and said first inner conductor joins said second inner conductor on a side wall thereof of greater width.

4. An electronic oven comprising upstanding structure defining a lower apparatus compartment and an upper box-like metal liner defining an upper cooking cavity, a generator disposed in said apparatus compartment for supplying ultra-high frequency electromagnetic wave energy, and a transmission line of the coaxial conductor type interconnecting said generator and said cooking cavity and including first and second sections disposed at an angle with respect to each other, whereby the electromagnetic wave energy is supplied into said cooking cavity via said transmission line from said generator, said first transmission line section including a first tubular outer conductor having a substantially circular cross section and a first enclosed inner conductor having a substantially circular cross section, said second transmission line section including a second tubular outer conductor having a substantially rectangular cross section and a second enclosed inner conductor having a substantially rectangular cross section, an outer circular fitting on one of the side walls of greater width of said second outer conductor and surrounding an opening provided therein, an inner circular fitting on the adjacent side wall of greater width of said second inner conductor, a first readily separable connection between one end of said first outer conductor and said outer circular fitting, and a second readily separable connection between the adjacent end of said first inner conductor and said inner circular fitting.

5. The electronic oven set forth in claim 4, and further comprising an electrical insulator mounted in said second outer conductor in alignment with said opening therein and supporting the adjacent end of said second inner conductor and said inner circular fitting thereon.

6. An electronic oven comprising upstanding structure defining a lower apparatus compartment and an upper box-like metal liner defining an upper cooking cavity, a generator disposed in said apparatus compartment for supplying ultra-high frequency electromagnetic wave energy, and a transmission line of the coaxial conductor type interconnecting said generator and said cooking cavity and including first and second and third sections disposed at angles with respect to each other, whereby the electromagnetic wave energy is supplied into said cooking cavity via said transmission line from said generator, said first transmission line section including a first tubular outer conductor having a substantially circular cross section and a first enclosed inner conductor having a substantially circular cross section, said second transmission line section including a second tubular outer conductor having a substantially rectangular cross section and a second enclosed inner conductor having a substantially rectangular cross section, said third transmission line section including a third tubular outer conductor having a substantially circular cross section and a third enclosed inner conductor having a substantially circular cross section, said second transmission section extending from adjacent

to said generator to the rear of said apparatus compartment, said first transmission line section having one end thereof connected to said generator and the other end thereof connected to one side of said second transmission line section adjacent to the front end thereof, said third transmission line section having one end thereof connected to the opposite side of said second transmission line section adjacent to the rear end thereof and having the other end thereof connected to said cooking cavity.

10. The electronic oven set forth in claim 6, wherein a decoupling insulator is provided in said third outer conductor to isolate the electrical potential on said second outer conductor from said cooking cavity.

8. The electronic oven set forth in claim 6, wherein the angle between said first transmission line section and said second transmission line section is substantially 90° and the angle between said second transmission line section and said third transmission line section is substantially 90°.

20. An electronic oven comprising upstanding structure defining a lower apparatus compartment and an upper box-like metal liner including a top wall and defining a cooking cavity, a metal distribution box supported upon said top wall exteriorly of said cooking cavity and provided with a bottom opening registering with a top window provided in said top wall, a generator disposed in said apparatus compartment for supplying ultra-high frequency electromagnetic wave energy, and a transmission line interconnecting said generator and said cooking cavity and including first and second sections disposed at an angle with respect to each other, whereby the electromagnetic wave energy from said generator is transmitted via said transmission line to said distribution box and is distributed from said distribution box through said bottom opening and said window into said cooking cavity, said first transmission line section including a first tubular outer conductor having a substantially circular cross section and a first enclosed inner conductor having a substantially circular cross section, said second transmission line section including a second tubular outer conductor having a substantially rectangular cross section and a second enclosed inner conductor having a substantially rectangular cross section, one end of said first outer conductor abutting and joining a side wall of said second outer conductor and surrounding an opening provided therein and the adjacent end of said first inner conductor projecting through said opening and abutting and joining a side wall of said second inner conductor, the end of said second outer conductor adjacent to said first outer conductor being closed and the other end of said second outer conductor abutting and joining a side wall of said distribution box and surrounding an opening provided therein and the adjacent end of said second inner conductor projecting through said opening and into said distribution box.

55. 10. The electronic oven set forth in claim 9, wherein said distribution box is of elongated form having a length that is substantially equal electrically to one wave length of the electromagnetic wave energy.

60. 11. The electronic oven set forth in claim 9, wherein said distribution box is of elongated form and said other end of said second outer conductor joins the side wall of said distribution box substantially midway between the ends thereof.

65. 12. The electronic oven set forth in claim 9, and further comprising a tuning rod mounted on the side wall of said distribution box opposite said opening therein and electrically coupled to the adjacent end of said second inner conductor for tuning said generator to said cooking cavity.

70. 13. The electronic oven set forth in claim 12, wherein in said tuning rod is adjustable along its longitudinal axis so as to provide a variable position thereof with respect to the adjacent end of said second inner conductor in

order to effect variable coupling therebetween for tuning said generator to said cooking cavity.

14. An electronic oven comprising an upstanding substantially box-like metal liner including a top wall and having a front opening and defining a cooking cavity, a metal front door cooperating with said liner and movable between open and closed positions with respect to said front opening, a metal distribution box supported upon said top wall exteriorly of said cooking cavity and provided with a bottom opening registering with a top window provided in said top wall, a transmission line of the coaxial conductor type including an outer conductor and an enclosed inner conductor, one end of said outer conductor joining one of the walls of said distribution box in surrounding relation with an opening therein, the adjacent one end of said inner conductor projecting through said opening into the interior of said distribution box and constituting a probe disposed in spaced relation with the walls of said distribution box and located above said bottom opening, means including an ultra-high frequency generator operatively connected to the other end of said transmission line for supplying ultra-high frequency electromagnetic energy to said probe with said front door in its closed position, whereby ultra-high frequency electromagnetic wave energy is radiated from said probe and is distributed from said distribution box through said bottom opening and said window into said cooking cavity, and a pane supported in covering relation with respect to said window so as to prevent oven gases from passing from said cooking cavity into said distribution box, said pane being highly transparent to the electromagnetic wave energy that is distributed therethrough from said distribution box into said cooking cavity.

15. A combination electric and electronic oven comprising an upstanding substantially box-like metal liner including a top wall and having a front opening and defining a cooking cavity, a metal front door cooperating with said liner and movable between open and closed positions with respect to said front opening, a metal distribution box supported upon said top wall exteriorly of said cooking cavity and provided with a bottom opening registering with a top window provided in said top wall, means for supplying ultra-high frequency electromagnetic wave energy into said distribution box with said front door in its closed position, whereby the electromagnetic wave energy is distributed from said distribution box through said bottom opening and said window into said cooking cavity, a pane supported in covering relation with respect to said window so as to prevent oven gases from passing from said cooking cavity into said distribution box, said pane being highly transparent to the electromagnetic wave energy that is distributed therethrough from said distribution box into said cooking cavity, an electric heating unit of the resistance conductor type and including two sections, and means for supporting the two sections of said electric heating unit in the upper portion of said cooking cavity adjacent to and somewhat below said top wall and respectively positioned outwardly on opposite sides of said window and thus out of the direct path of distribution of the electromagnetic wave energy from said distribution box into said cooking cavity.

16. The combination electric and electronic oven set forth in claim 15, wherein the two sections of said electric heating unit are supported from said top wall and are respectively positioned outwardly on the opposite front and rear sides of said window.

17. An electronic oven comprising an upstanding substantially box-like metal liner including top and bottom walls and a pair of side walls and a rear wall and having a front opening and defining a cooking cavity, a metal front door cooperating with said liner and movable between open and closed positions with respect to said front opening, a metal distribution box supported upon said top wall exteriorly of said cooking cavity and provided with a bottom opening registering with a top window pro-

vided in said top wall, an ultra-high frequency generator located below said bottom wall and exteriorly of said cooking cavity, a transmission line disposed exteriorly of said cooking cavity and interconnecting said generator and said distribution box, whereby the electromagnetic wave energy from said generator may be supplied via said transmission line into said distribution box and distributed therefrom through said bottom opening and said window into said cooking cavity, a pane supported in covering relation with respect to said window so as to prevent oven gases from passing from said cooking cavity into said distribution box, said pane being highly transparent to the electromagnetic wave energy that is distributed therethrough from said distribution box into said cooking cavity, said distribution box being electrically connected to said top wall, one end of said transmission line being electrically connected to said generator and the other end of said transmission line being electrically connected to said distribution box, and means including a decoupling insulator provided in said transmission line intermediate the ends thereof for isolating the electrical potential of said generator from said liner.

18. An electronic oven comprising an upstanding substantially box-like metal liner including top and bottom walls and a pair of said walls and a rear wall and having a front opening and defining a cooking cavity, a metal front door cooperating with said liner and movable between open and closed positions with respect to said front opening, a metal distribution box supported upon said top wall exteriorly of said cooking cavity and provided with a bottom opening registering with a top window provided in said top wall, an ultra-high frequency generator located below said bottom wall and exteriorly of said cooking cavity, a transmission line disposed exteriorly of said cooking cavity and interconnecting said generator and said distribution box, whereby the electromagnetic wave energy from said generator may be supplied via said transmission line into said distribution box and distributed therefrom through said bottom opening and said window into said cooking cavity, and a pane supported in covering relation with respect to said window so as to prevent oven gases from passing from said cooking cavity into said distribution box, said pane being highly transparent to the electromagnetic wave energy that is distributed therethrough from said distribution box into said cooking cavity, said generator being located beneath said bottom wall and forwardly of said rear wall, said transmission line including first and second and third sections, said first transmission line section being disposed substantially horizontally and below said bottom wall and being connected adjacent to the front end thereof to said generator, said third transmission line section being disposed substantially horizontally and above said top wall and being connected adjacent to the front end thereof to said distribution box, said second transmission line section being disposed in upstanding position and rearwardly of said rear wall, the lower end of said second transmission line section being connected to said first transmission line section adjacent to the rear end thereof, and the upper end of said second transmission line section being connected to said third transmission line section adjacent to the rear end thereof.

19. The electronic oven set forth in claim 18, wherein said transmission line is of the coaxial conductor type including an outer conductor and an enclosed inner conductor.

20. An electronic oven comprising an upstanding substantially box-like metal liner including top and bottom walls and a pair of side walls and a rear wall and having a front opening and defining a cooking cavity, a metal front door cooperating with said liner and movable between open and closed positions with respect to said front opening, a metal distribution box supported upon said top wall exteriorly of said cooking cavity and provided with a bottom opening registering with a top window provided

in said top wall, an ultra-high frequency generator located below said bottom wall and exteriorly of said cooking cavity, a transmission line disposed exteriorly of said cooking cavity and interconnecting said generator and said distribution box, whereby the electromagnetic wave energy from said generator may be supplied via said transmission line into said distribution box and distributed therefrom through said bottom opening and said window into said cooking cavity, and a pane supported in covering relation with respect to said window so as to prevent oven gases from passing from said cooking cavity into said distribution box, said pane being highly transparent to the electromagnetic wave energy that is distributed therethrough from said distribution box into said cooking cavity, said transmission line being of the coaxial conductor type including an outer tubular conductor and an enclosed inner conductor, said transmission line comprising at least four series connected sections, each odd one of said transmission line sections including a tubular outer conductor having a substantially circular cross section and an enclosed inner conductor having a substantially circular cross section, and each even one of said transmission line sections including a tubular outer conductor

having a substantially rectangular cross section and an enclosed inner conductor having a substantially rectangular cross section.

21. The electronic oven set forth in claim 14, wherein said distribution box is of elongated form and extends substantially parallel to and above the top of said front opening.

22. The electronic oven set forth in claim 21, wherein said distribution box is located substantially centrally of said top wall.
